(57) **CLAIM**

The ornamental design for a water wagon frame, as shown and described.

DESCRIPTION

FIG. 1 is a front top right perspective view of the water wagon frame of the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the drawings illustrating the ride-on wagon in broken lines form no part of the design claim for the water wagon frame.

1 Claim, 7 Drawing Sheets
